HORACE W. TURNER, OF PHOENIX, NEW YORK

HEATER

Application filed January 31, 1930. Serial No. 424,841.

This invention relates to means for heating automobiles, airplanes, and the like, and has for its object to provide an elongated hollow body, which may be mounted directly upon the exhaust manifold of an air-cooled motor or engine, without changing or disturbing the manifold, whereby a continuous supply of fresh air may be drawn from the fan casing and forced through said body, where it may be suitably tempered by heat derived from the exhaust of the engine. A further object is to provide such a hollow heating member having open ends and a normally open bottom, which faces the exhaust manifold, and facilitates the free upward radiation of the heat, which is absorbed by the continuous stream of fresh air supplied by the fan, the interior of said body being fitted with a staggered arrangement of baffles, which compel the air stream to flow in a course that undulates vertically throughout the length of the body, the arrangement of the baffles being such that the air is deflected toward the manifold and re-heated at regularly recurring intervals during its passage through said body. A further object is to provide simple means for clamping the heater body to the exhaust manifold. And a further object is to provide novel metallic packing means for sealing the joint between the bottom of the heater and the top surface of the exhaust manifold, to prevent leakage or deterioration of the heated air.

I attain these objects by the means set forth in the detailed description which follows; and as illustrated by the accompanying drawing, in which—

Figure 1 is a broken side elevation of an air-cooled internal combustion engine, showing my heater imposed upon the exhaust manifold. Fig. 2 is an enlarged top plan view of the heater. Fig. 3 is a vertical longitudinal section, taken on line 3—3 of Fig. 2, showing the orderly arrangement of the baffles that effect the serpentine flow of the heated air. Fig. 4 is an enlarged vertical cross-section, taken on line 4—4 of Fig. 1. And Fig. 5 is an enlarged vertical cross-section, taken on line 5—5 of Fig. 2.

50 In the drawing, 2 represents conventionally

an air-cooled type of internal combustion engine for automobile and airplane service. 3 represents the exhaust manifold, which is common to the several cylinders 2'. And 4 represents the usual fan by which the cooling 55 blasts are generated, the fan being enclosed by a casing 4'.

My automobile heater comprises an elongated hollow cast or sheet metal body 5, of any suitable length and cross-sectional shape 60 and area having reduced open end portions 5'—5^a, to which flexible or other receiving and discharging tubes, as 6—6', may be applied, as shown in Figs. 1 and 2. In practice, the body 5 is preferably mounted upon the 65 top surface of the manifold 3 to which it may be readily and quickly secured by means of a number of stirrup-like clamps 7, the arm 7' of which may pass through lateral perforated lugs as 5^b. The free ends of said arms are 70 preferably threaded to receive nuts 7^a between which and the top surface of the lugs are preferably interposed relatively stiff compression springs 7^b, to provide a certain amount of cushioning to aid in adjusting and 75 conforming the heater body to the manifold, as well as to regulate the pressure upon a packing that intervenes the body and the manifold. The intake tube 6 taps the fan casing 4' and diverts a portion of the cooling 80 fluid to the heater 5, and the discharge tube 6' may conduct the hot air to different parts of the tonneau (not shown) of the vehicle. The bottom of the heater body 5 is normally open 85 and is preferably formed with a continuous marginal groove 5^c, which faces the manifold and in which is disposed a tubular packing 8, preferably consisting of copper, or annealed brass of suitable gage, which may be partially collapsed by pressure exerted by the 90 springs 7^b by the tightening of the nuts 7^a, as may be understood by comparing Figs. 4 and 5. In this way, the packing 8 may be made to conform to any unevenness of the surface of the manifold and effect an air-tight joint. 95 According to the present showing, the body 5 of the heater is substantially square in cross-section, and its interior is fitted with two series of obliquely disposed baffles, 9 and 9'. The baffles 9 are preferably secured to the 100

top wall of the body 5 by rivets 9^a. The baffles 9' rise from the bottom plane of, and may be cast with the body, or they may be detachably secured by any of the well-known means. The alternate arrangement of the baffles effect vertical undulations of the stream of air, as may be understood from the tortuous course of the arrows in Fig. 3. By this peculiar arrangement of the baffles, the air stream approaches and recedes from the highly heated top surface of the manifold at regularly recurring intervals throughout the length of the heater body, which tends to progressively increase the temperature by intermittently re-heating the air while the latter pursues its serpentine course. By this means, the highest possible degree of heat reduced by radiation from the top or hottest portion of the manifold may be generated in the body of the heater and distributed by the conductor 9'.

Having thus described my invention, what I claim, is—

1. In an air-cooled type of internal combustion engine having an exhaust manifold and an encased fan, a heater comprising an oblong hollow body having open ends, one end communicating with the fan chamber, the side of said body that faces the manifold being open, and said body being provided interiorly with oblique baffles arranged to direct the stream of air received from said chamber in an undulating course that effects the re-heating and progressive raising of the temperature of the air, means to clamp the heater body to the manifold, and a continuous tubular packing interposed between the open side of the heater and the adjacent surface of the manifold.

2. A heater for automobiles and the like, comprising an elongated hollow body open at its ends adapted to be mounted upon the exhaust manifold of an internal combustion engine and being provided with means to receive air from the fan-casing of the engine cooling system, said body having a normally open bottom that faces the manifold, and a staggered arrangement of baffles that cause the stream of air to undulate and approach the radiating surface of the manifold at regularly recurring intervals to progressively increase the temperature of the air as it pursues its course through the body, means acting under compression to resiliently clamp the heater body to the manifold, and a packing adapted to collapse under said compression to seal the joint between the heater and manifold.

3. In an air-cooled type of internal combustion engine having an exhaust manifold and a fan, a heater comprising an oblong hollow body having open ends, one adapted to communicate with said fan, and having an open bottom to admit the heat radiated by the manifold, said body being provided interiorly with two series of staggered oblique baffles

adapted to direct the stream of air received from the fan in a course that undulates vertically in a plane that substantially parallels the abutting face of the manifold, whereby to intermittently increase the temperature of the air as it flows through said body, means to clamp the heater body to the manifold, and a continuous collapsible packing interposed between the bottom edges of the heater body and the adjacent surface of the manifold.

4. A hot air generator for heating automobiles and the like, comprising an elongated hollow body open at its ends and adapted to be mounted upon the exhaust manifold of an air-cooled internal combustion engine and to communicate with and receive air from the fan chamber of the engine cooling system, said body having an open bottom that faces the manifold and being fitted interiorly with staggered baffles arranged in opposing series, that cause the stream of air to flow in a serpentine course that substantially parallels the top of the manifold, one series of baffles adapted to deflect the stream of air towards the manifold at regular intervals throughout the length of the body to cause the temperature of the air to increase progressively, a series of stirrups to clamp the body to the manifold, said stirrups engaged with the bottom of, and extending over the sides of the manifold, and means to connect the ends of said stirrups to the body.

In testimony whereof I affix my signature.
